CATHODE-RAY BEAM DEFLECTING CIRCUIT

Otto H. Schade, West Caldwell, N. J., assignor to
 Radio Corporation of America, a corporation of
 Delaware

Application January 13, 1945, Serial No. 572,712

10 Claims. (Cl. 315—27)

1

The present invention relates to cathode ray beam deflecting circuits, especially circuits of the kind adapted for use in television transmitters and receivers, and in which the wave form of the current flowing through the beam deflecting coils is of such shape as to cause the movement of the cathode ray beam to be at a constant rate with respect to time during the useful part of each deflection cycle.

It is a customary practice in circuits of the above type to provide an electron discharge tube having a relatively high power output for supplying energy to the beam deflecting coils. Across the deflecting coils a so-called damping tube is frequently connected. This tube is conventionally represented as comprising an inverted diode, the purpose of which is to eliminate any high-frequency oscillations which would otherwise be set up in the deflecting coils, and also to aid in the deflection of the cathode ray beam during a part of each deflection cycle.

The inverted diode serves as a periodic discharge path for the electromagnetic energy stored in the deflecting coils or other circuit inductance at the end of the deflection cycle. In the absence of the diode, this stored energy would normally produce relatively high-frequency oscillations in the systems, with the result that the deflection of the cathode ray beam during the initial part of its deflection cycle would be non-linear. When the diode is used as a damping tube, only one-half cycle of free oscillation is permitted to take place, and thereafter the energy contained in the deflecting coils or other circuit inductance is used for the initial part of the next useful deflection cycle.

When a conventional power tube and an inverted diode are used as above described, it is found that the summation characteristic of these tubes is not linear, and as a consequence distortion of the reproduced image may occur. To overcome this condition, an arrangement has been proposed in which feedback voltages are applied to the control electrode of the power tube. A circuit employing the use of feedback voltage variations is illustrated and described in Schade application Patent No. 2,309,672, granted February 2, 1943.

It has also been found that linearity of deflection may be obtained by modifying the characteristics of the inverted diode or suppressor tube. To permit such modification, the diode is replaced by a triode or multi-grid electron discharge tube, so that voltage variations of a par-

2

ticular wave form may be applied to the control electrode of the discharge tube to alter its conduction characteristics. A system of this nature is disclosed in United States Patent No. 2,382,822 granted to Otto H. Schade. When the conduction characteristics of the suppressor tube are varied during each deflection cycle, linearity of deflection may be produced without resorting to the use of feedback voltage variations applied to the control electrode of the power tube.

10 A scanning circuit such as shown in above-mentioned Patent No. 2,382,822, in which a controlled suppressor or damping tube is utilized with transformer coupling between power tube and deflection coils, has a number of advantages over the so-called "direct-drive" systems when the coupling transformer is designed with a step-down ratio. Among these advantages is the fact that the capacitances of yoke, cable, and damping tube are removed from the primary and placed in the secondary circuit, permitting the building up of a higher plate circuit inductance to thereby result in a gain in yoke current. Also, the surge voltage on the damping tube, yoke, and cable is reduced in value so that the insulation requirements are lessened.

15 However, operation of a transformer-coupled circuit such as shown in Patent No. 2,382,822 normally requires that the polarity of the current in the secondary circuit be the same as that in the primary or power tube circuit. For that reason the damping tube, which is conductive alternately with the power tube and with power supplied by the primary circuit, must be actually 20 "inverted" or, in other words, positioned so that its cathode is connected to the high potential end of the deflecting coils. From a practical standpoint, a circuit of this type not only requires an isolation transformer for the tube heater, but in 25 addition necessitates employing a damping tube designed especially for such a mode of operation. Furthermore, the voltage of the control electrode in the damping tube is "floating" at surge potential, and is difficult to measure or adjust.

30 35 40 45 According to one feature of the present invention, I provide means whereby the damping or suppressor tube may be operated with its cathode at A.-C. ground potential, thereby permitting the tube heater to be grounded and eliminating the necessity for an isolation transformer or other special circuit components.

50 55 As above brought out, the power tube builds up magnetic energy in the deflection coils or other circuit inductance in the latter part of the scanning period. During retrace, the polarity of

the magnetic field, and consequently the current flow in the circuit inductance, is reversed in one-half cycle of free oscillation. The "reversed" current is now forced to decrease at the proper rate over the controlled suppressor or damping tube, and this "reversed" current supplements the power tube current to a linear summation characteristic. In order to obtain linearity of this summation characteristic, the wave form of the control voltage on the grid of the suppressor tube must be such as to effect a proper control of the rate of current decrease through the damping tube.

In Patent No. 2,382,822, above mentioned, the control grid voltage for the suppressor tube is obtained by differentiation of the surge voltage across the deflecting coils. The result of this differentiation is a falling sawtooth voltage corresponding with reversed polarity to the voltage applied to the grid of the power tube.

According to a further feature of the present invention, I provide means for deriving for the grid of the suppressor tube a control voltage which has two exponential sections, and is of such form that parasitic oscillations in the circuit inductance appear in proper phase in the grid circuit of the suppressor tube to produce degeneration of such oscillations in the anode circuit. The control grid voltage thus derived is especially effective in damping out the first strong parasitic oscillations at the beginning of scansion.

A complete current cut-off in the plate circuit of the power tube during retrace periods is essential for high efficiency. This is very noticeable in circuits having a low shunt loss, such as that herein disclosed, where the plate impedance of a partially cut-off tube represents a large portion of the shunt. Often, however, the synchronizing pulse generated by means such as a blocking oscillator is too short for complete power tube cut-off.

According to a still further feature of the present invention, a negative peaking pulse of proper duration is derived from the secondary circuit and fed back to the control electrode of the power tube. It has been found that no adjustment of driving voltage, wave shape, bias, or blocking oscillator peaking in the circuit gives the efficiency obtained with a negative peaking pulse of proper duration, especially when it is appreciated that a "square" current cut-off such as that obtained by the means herein disclosed reduces to a considerable extent the plate dissipation in the power tube.

It is, therefore, one object of the present invention to provide a circuit for electromagnetically deflecting a cathode ray beam in which linearity of deflection may be insured through an improved control circuit for the damping or suppressor tube.

Another object of the present invention resides in the provision of a controlled suppressor tube in a circuit arrangement for electromagnetically deflecting a cathode ray beam, and so controlling the suppressor tube by means of a voltage having a wave form of exponential shape that the summation of the current flow through the suppressor tube and through the deflection power tube during each cycle will produce substantially linear deflection of the cathode ray beam.

A still further object of the present invention resides in the provision of a system for electromagnetically deflecting a cathode ray beam in which a controlled suppressor or damping tube

is used, and in which means are provided for operating the cathode of the suppressor or damping tube at or substantially at alternating current ground potential.

An additional object of the present invention is to provide means for deriving from the secondary circuit of a scanning system in which the power tube is connected to the deflecting coils through a coupling transformer a negative peaking pulse of proper duration and feeding back this pulse to the control electrode of the power tube.

Other objects and advantages will be apparent from the following description of a preferred form of the invention and from the drawing, in which:

Fig. 1 shows schematically a cathode ray beam deflecting circuit in accordance with the present invention; and

Fig. 2 is a set of waveforms illustrating the operation of the circuit of Fig. 1.

Referring now to Fig. 1, there is shown a deflection power tube 10 which supplies current to a pair of deflecting coils 12 through a transformer 14. Tube 10 is preferably of a type such as the RCA 807 and includes a cathode, a control electrode, a screen electrode, and an anode. The anode of tube 10 is connected to the positive terminal 16 of a suitable source of potential (not shown) through the primary winding of transformer 14, so that the latter represents the load circuit of the tube. Between the cathode of tube 10 and ground is connected a bias resistor 18 which is shunted by a by-pass condenser 20. The screen electrode of tube 10 is maintained at proper potential with respect to the cathode by means of two series resistors 22 and 24 connected between the screen electrode and the positive terminal 16 of the potential source. Resistor 24 is adjustable. A screen by-pass condenser 26 is provided between the screen electrode and ground.

For deriving a control voltage for the control electrode of tube 10, there is provided a condenser 28 which is charged from the source of potential connected to the terminal 16 through resistors 22 and 24 and an additional charging resistor 30. The voltage developed on condenser 28 is applied to the control electrode of tube 10 through a coupling condenser 32. A resistor 34 of relatively high value is connected between the control electrode of tube 10 and ground. The charging rate of condenser 28 may be varied by adjustment of resistor 24, as will be later described.

It is desired that the voltage appearing on the control electrode of tube 10 be of a shape such as represented by wave form 36 or, in other words, of rising sawtooth configuration. In order to obtain a curve of this nature, there is provided means for discharging the condenser 28, this means in the form shown comprising a grid-controlled discharge tube 38 of any suitable type, with the discharge tube anode being connected to the upper plate of condenser 28. Discharge tube 38 is normally biased to cut-off by some conventional means such as a bias resistor 40 connected between the grid of the tube and the negative terminal of a source of bias potential (not shown).

When tube 38 is non-conductive, condenser 28 will be charged through resistors 22, 24, and 30 to produce a charge on condenser 28 such as represented by the rising positive portion of sawtooth wave 36. By selecting elements having a suitable time constant, this rising positive portion of wave 36 may be made exponential or substantially linear, its amplitude being con-

trolled by means of adjustable resistor 24 to vary accordingly the output of power tube 10 as applied to deflection coils 12 and hence the cathode ray beam deflection angle.

When positive pulses, such as indicated at 42, are applied to the grid of discharge tube 38, the latter becomes conductive to discharge condenser 28. The negative peaks of wave 36 are obtained, in a manner hereinafter to be more fully described, by connecting the lower plate of condenser 28 to a sliding contact 44 on a peaking resistor 46 the ends of which are connected respectively to ground and to a point on the secondary winding of transformer 14. A by-pass condenser 48 is provided between sliding contact 44 and ground.

Since resistor 24 is connected between the screen electrode of power tube 10 and the positive terminal 16 of the potential source, adjustment of resistor 24 provides a means for varying the power output of tube 10 by changing the potential applied to the screen electrode and simultaneously the grid signal amplitude because of the connection of the charging resistor 30 to the screen electrode.

As above stated, power tube 10 is coupled to the deflection coils 12 through a transformer 14. The secondary winding of transformer 14 is wound in a direction opposite to that of the primary winding, so that the adjacent ends of the two windings in the drawing will be of opposite polarity as indicated. Across the secondary winding of transformer 14 a controlled suppressor tube 50 is connected which tube is shown as a twin triode enclosed in a common envelope. Tube 50 preferably has a low amplification factor and high perveance.

The joined anodes of suppressor tube 50 are connected to the upper end of the secondary winding of transformer 14 and also to the upper end of the deflection coils 12. The joined cathodes of suppressor tube 50 are connected through an adjustable load resistor 52 to the lower end of the secondary winding of transformer 14. A by-pass condenser 54 is shunted around resistor 52, while a further by-pass condenser 56 is connected between the lower end of resistor 52 and ground.

The lower end of resistor 52 is additionally connected to a tap on a centering resistor 58 the ends of which are connected respectively to ground and to a negative tap on the source of potential (not shown) which has its positive terminal indicated by the reference numeral 16. A sliding contact 60 on resistor 58 is connected to the lower end of deflection coils 12. By varying the position of contact 60, the amount of direct current flowing through deflection coils 12 may be altered so as to control the centering of the cathode ray beam. The lower end of deflection coils 12 is connected to ground through a by-pass condenser 62.

It will be noted that in the circuit arrangement above described the anodes of suppressor tube 50 are connected to the upper or high potential end of deflection coils 12, while the cathodes of suppressor tube 50, insofar as alternating currents are concerned, are grounded through the condensers 54 and 56. For that reason the high alternating current potentials developed during operation of the system are not impressed on the cathodes of tube 50, these elements instead operating substantially at A-C. ground potential.

The voltage variations applied to the control electrode of power tube 10 are in the form of a

rising sawtooth voltage, as represented by the curve 36, which together with the bias potential applied to the control electrode is such as to produce a rising output current in tube 10.

While the voltage applied to the control electrode of tube 10 acts to cut off plate current in the tube at the beginning of retrace time, the current in the secondary circuit does not disappear instantaneously because of the inherent distributed capacity across the secondary winding of transformer 14 and across the deflection coils 12. This distributed capacity is, at the instant of the beginning of retrace, charged to a relatively low voltage.

15 The inductance of these elements, together with the distributed capacity thereacross, forms a tuned circuit in which high-frequency oscillations will be produced in the absence of the controlled suppressor tube 50. The oscillations 20 begin with the start of retrace time, and continue for substantially one-half cycle of the natural period of oscillation of the circuit. After one-quarter cycle, the current in the deflecting coils reverses, and the oscillation is stopped after one-half cycle near the negative current peak by reason of the suppressor tube 50. During the retrace time, that is, during the half cycle of the natural period of oscillation of the secondary circuit, the current in both tubes 10 and 50 is completely blocked, the voltage across the deflecting coils and the transformer secondary rising to a high peak value at one-quarter cycle when the current passes through zero. A new deflection cycle starts after the one-half cycle of free oscillation, at which time the voltage appearing across the deflecting coils and transformer secondary is maintained substantially uniform.

In order that linear deflection may be produced, it is necessary that the rate of change of 40 the current in the secondary circuit be maintained constant during the deflection cycle. The grid voltage 36 of the power tube 10, curve a, Fig. 2, and the bias potential of that tube cause the plate current of tube 10 to increase as shown in 45 Fig. 2b after the beginning of the deflection cycle. The voltage variations applied to the controlled suppressor tube 50, however, such as those indicated by the wave form 64 in curve E, Fig. 2, are such that the suppressor tube 50 begins to 50 conduct immediately following the retrace time, and operates to produce a decreasing plate current, curve c, Fig. 2, which supplements the plate current of power tube 10 to a linear deflection current characteristic as shown in Fig. 2D in spite 55 of fluctuations of the individual tube currents.

The voltage variations 64 applied to the control electrodes of the suppressor tube 50 and the normal bias of the control electrodes must, therefore, be so adjusted as to give the desired wave form to the anode current permitted to flow through the suppressor tube. When the wave form of the current output of power tube 10 is properly matched with the wave form of the current output of the suppressor tube 50 as shown in 60 curves b and c, the summation of these currents will be a straight line as illustrated in curve D, and represents the current actually flowing through the deflection coils during each deflection cycle. The most positive part of the wave form 64 occurs immediately following the retrace time, with negative peaking impulses occurring as shown in curve E concurrently with the retrace time.

After the initiation of current flow in the suppressor tube 50, the waveform 64 of the potential

on the control electrodes as represented in curve E is changed exponentially in a negative direction. This reduces at a predetermined rate the current flow through the suppressor tube 50, thereby resulting in a summation current that is linear and that will produce linear deflection of the cathode ray beam.

The means for obtaining a voltage variation having a wave form such as represented by the curve 64 includes a differentiating network comprising a condenser 66 and resistors 68 and 74, the upper plate of condenser 66 being connected to the upper end of the secondary winding of transformer 14. Bias for the control electrodes of suppressor tube 50 is obtained by grid voltage rectification and grid current in resistor 70 in parallel with a by-pass condenser 72, one end of resistor 70 being connected to the joined cathodes of suppressor tube 50. Between resistors 68 and 70 is an adjustable resistance element comprising a potentiometer 74, the latter acting as a linearity control.

The voltage output of the differentiating network as developed on resistors 68 and 74 is applied to one control electrode of suppressor tube 50 through a shaping resistor 76, and to the other control electrode of suppressor tube 50 through a further shaping resistor 78. Resistors 76 and 78 are of equal value so that the voltage appearing on each of the control electrodes of suppressor tube 50 will have the same wave form.

The voltage appearing on the control electrodes of suppressor tube 50, as represented by the wave form 64, has two exponential sections respectively occurring during intervals t_1 and t_2 as indicated in Fig. 2E. When the control electrodes of suppressor tube 50 are positive, current flows through resistors 76 and 78 and the grid-cathode impedance of tube 50. This total impedance shunts the differentiating resistor 68 so as to change the differentiating constant of the differentiating network 66, 68. The result is a fast-decaying transient during interval t_1 , and this voltage variation produces a heavy initial plate current output from suppressor tube 50 which is effective in damping out the first strong parasitic oscillations in the circuit.

The second section of wave form 64 is a slow-decaying voltage during interval t_2 caused by the resistor 68 when the control electrodes of suppressor tube 50 are negative and no current flows through resistors 76 and 78. These resistors 76 and 78, therefore, act in effect as current limiters to vary the impedance of the control electrodes of suppressor tube 50.

The result of the above mode of operation is to improve the linearity of the system by regulating the current output of the suppressor tube by a control voltage of such form as to cause the current flow through the suppressor tube to decrease in a predetermined manner.

As set forth above and as shown in Figs. 1 and 2, the wave form 36 of the voltage appearing on the control electrode of power tube 10 has high negative peaks. These peaks are obtained by means of a peaking resistor 46 having a sliding contact 44 connected to the lower plate of charging condenser 28. One end of peaking resistor 46 is connected to a tap 84 on the secondary winding of transformer 14, permitting a negative peaking pulse of proper duration to be fed back from the transformer 14 to the control electrode of power tube 10. The amplitude of the peaking pulse may be varied by adjustment of contact 44.

It has been found in practice that the follow-

ing values are suitable for the circuit components used in the system herein described. However, these values are being given merely as an example, and it is to be understood that other values may be substituted for any or all of the components if desirable or necessary.

While I have shown and described, and have pointed out in the annexed claims, certain novel features of my invention, it will be understood that various omissions, substitutions, and changes in the form and details of the system illustrated may be made by those skilled in the art without departing from the spirit of the invention.

40 I claim:

1. A deflecting system for a cathode ray beam comprising a deflection power tube having cathode, control and anode electrodes; a beam deflection coil, a transformer having its primary winding in the anode-cathode circuit of said power tube and its secondary winding connected across said deflection coil, means for applying voltage variations of predetermined waveform between the control electrode and cathode of said power tube to supply said deflection coil with an approximately sawtooth current through the transformer, said transformer being wound so that the corresponding ends of its primary and secondary windings have opposite relative polarities, a damping tube having cathode, control and anode electrodes; means connecting the anode-cathode electron path of said damping tube across said deflection coil, the anode of said damping tube being connected to that end of said coil more remote from ground, means for differentiating the voltage developed across said deflection coil and applying said differentiated voltage to the control electrode of said damping tube, and means including the control electrode-cathode impedance of said damping tube for modifying the wave shape of said differentiated voltage to provide a damping tube current which supplements the power tube current whereby their algebraic sum in the deflection coil is substantially linear.

2. A deflecting system according to claim 1 wherein said last mentioned means comprise a resistor connected in series between the control electrode of said damping tube and said differentiating means.

3. In a beam deflecting system of the type having a transformer secondary, a damping circuit, and a deflection coil all connected in parallel, the combination of a damping tube having cathode and anode electrodes in said damping circuit, a control electrode in said damping tube, differentiating means connected between said anode and cathode, and a resistance connecting the output of said differentiating means to said control electrode, said resistance having such value relative to the other circuit components to make the damping tube current supplement the current from said transformer secondary, whereby the algebraic sum of said currents in the deflection coil is substantially linear.

4. A deflecting system according to claim 1 comprising in addition, means for applying a portion of the energy developed across the secondary winding of said transformer, during retrace, as a negative voltage to the control electrode of said power tube.

5. In a television circuit, a power tube, a deflection coil, a transformer coupling the output of said power tube to said coil, a damping tube connected across the secondary winding of said transformer and across said coil, said damping tube having a control electrode, means for differentiating the voltage variations induced across said coil, means in series with said control electrode for shaping the differentiated voltage variations to provide a damping tube current which is complementary to the current from said transformer secondary winding, whereby the algebraic sum of said currents in the deflection coil is substantially linear.

6. In a beam deflecting system the combination of, a power tube having an input circuit and an output circuit, a deflection coil, means coupling said output circuit to said deflection coil, a damping circuit including a unilaterally conducting device connected across said coupling means, the arrangement being such that when the output current of said power tube is interrupted the consequent collapse of flux in said deflection coil induces a high potential in said output circuit of a polarity in the direction of conduction of said power tube and in the direction of non-conduction of said unilateral device; a peaking resistor in said input circuit, and means connected between said peaking resistor and said coupling means for feeding back a portion of said induced high potential to increase the blocking effect produced by said peaking resistor on the control electrode of the power tube for the duration of said high potential.

7. In a beam deflecting system the combination of, a power tube having at least a cathode, a control electrode, and an anode; a transformer having its primary winding connected between said anode and cathode, a deflection coil connected across a secondary winding of said transformer, a damping circuit including a unilaterally conducting device connected across the secondary winding and the coil, means including a peaking resistor connected between said control electrode and cathode to develop voltage variations of sawtooth waveform, means to apply the developed voltage variations to said control electrode, and a feed-back connection from a point

on the secondary winding of said transformer to said peaking resistor to feed back an impulse of negative polarity to said control electrode.

5 8. The combination of claim 5, in which said voltage variations periodically reverse in polarity, and in which said differentiating means includes a resistance-condenser combination the resistance portion of which is connected in the control electrode-cathode circuit of said damping tube, 10 whereby, when said voltage variations are of positive polarity, current will flow between the cathode and control electrode of said damping tube through said shaping means to effectively shunt the resistance portion of said resistance-condenser combination and thereby alter the differentiating constant of said differentiating means.

9. A circuit for deflecting a cathode ray beam during active and retrace intervals comprising the combination of an output tube having at least 15 a cathode, a control electrode and an anode, an input circuit for applying deflection signal potentials to the control electrode-cathode circuit of said output tube, a deflection coil, an output circuit including the anode-cathode elements of 20 the output tube to connect the tube output for energizing the deflection coil, damping means for the deflection coil, a circuit connected to the tube output circuit for deriving impulses during deflection retrace intervals, and for supplying 25 said impulses to the tube input circuit to increase the effective potential between the tube control electrode and cathode thereby to hold the tube at at least cutoff potential during the retrace interval, a condenser included 30 in the input circuit of said output tube, means 35 to couple one electrode of said condenser to the control electrode of said output tube, and means including an impedance to connect the other electrode of said condenser to a point of 40 fixed potential, and wherein the derived impulses are applied to a point on said impedance.

10. A circuit for deflecting a cathode ray beam during active and retrace intervals comprising the combination of an output tube having a cathode, 45 a control electrode, and an anode, a condenser connected in the control electrode-cathode circuit of said tube, a deflection coil, an output circuit including the anode-cathode elements of 50 said output tube connecting the tube output to the deflection coil, damping means for the deflection coil, means for generating a saw-tooth wave of voltage across said condenser, an auxiliary circuit connected to the tube output circuit for deriving impulses during deflection retrace intervals, 55 means connecting said auxiliary circuit in series with said condenser for maintaining the output tube at cutoff during the retrace interval.
